CARL WILHELM MÜLLER, OF DRESDEN-WEISSE HIRSCH, GERMANY

ADHESIVE APPLYING DEVICE FOR CIGARETTE MACHINES, IN WHICH THE ADHESIVE IS FORCED OUT OF RESERVOIRS INTO DISTRIBUTING NOZZLES

Application filed March 12, 1931, Serial No. 522,108, and in Germany November 20, 1930.

In cigarette machines methods are known of using a reservoir for the adhesive material from which the adhesive is expelled by a piston into the distributing nozzle. The spindle 5 of the piston is displaced gradually by a weight or a worm drive or the like.

During working the entire cigarette machine must often be stopped, but it is often necessary for parts of this machine, particularly the tobacco rod to be provided with a coating of cigarette paper, to move forward without causing an adhesion. In both cases care must be taken to ensure that the supply of adhesive is immediately discontinued, and 15 with the modern very rapidly running machines it is sometimes a question of fractions of seconds. In order to stop the supply of adhesive it has hitherto been necessary for the attendant to do this by removing the 20 weight or stopping the worm gear or the like, which takes time and requires that attention be given to a special part of the machine.

In contrast with the above the present invention consists in that with the reservoir 25 over the supply of adhesive there is connected a compressed air pipe which, for the purpose of reducing the air pressure on the adhesive, is cut off from the supply of compressed air by a regulating valve, and at the same time 30 connected with the atmosphere.

In this manner, by means of a single hand operation or purely mechanically by the actuating mechanism, the regulating valve can be moved in one or the other direction, so 35 that the air pressure is suddenly and absolutely cut off, which pressure alone controls the feeding of the distributing nozzles.

The regulating valve is preferably controlled by the actuating mechanism in such 40 manner that when the machine is stopped it is closed in the sense of cutting off the supply of compressed air; a hand control is also provided for the valve, the disengaging lever being arranged in the vicinity of the point where 45 adhesive is applied, so that the valve can easily be attended to whilst observation of the application of adhesive is carried on.

One form of construction of the invention is illustrated in the annexed drawings, in 50 which:—

Fig. 1 is a diagrammatic front view of the cigarette machine to which the new device has been fitted.

Fig. 2 is an end view seen in the direction indicated by the arrow in Fig. 1. 55

Fig. 3 is a front view on an enlarged scale of a part of the cigarette machine.

As is well known the cigarette rod St is provided in the former 1 with the envelope of cigarette paper, of which one longitudinal edge 2 projects from the former and is provided with adhesive by means of the disc 3, and is then secured to the already enveloped rod. The roller 3 is provided with adhesive in known manner by the distributing roller 4. The adhesive is passed to this distributing roller through the nozzle 5. This nozzle is connected with the adhesive container 7 by a pipe 6. The lid 8 of this container communicates with a compressed air pipe 9, connected to the compressed air chamber 11 by the pipe 10. The compressed air is passed through the pump 12 to the compressed air chamber. The pump is driven by the motor 19. The pump and the motor are mounted 70 on the machine frame A which rests on the supports B. 75

In the pipe 9 a valve 13 is inserted. This valve is connected to rods 14, 15, 16 and 17 at the end of which is a disengaging lever 18. 80 This disengaging lever is fitted in the vicinity of the point of adhesion in such manner that it can be manipulated with ease while watching the point of adhesion.

The valve is arranged in known manner in such a way that by suitable adjustment of the lever 18 the supply passage for the compressed air to the container 7 is closed and at the same time the latter is connected with the atmosphere, so that the pressure in the 85 container 7 can be cut off quite suddenly.

It may be remarked that in the container 7 a disc or the like resting on the adhesive is actuated in known manner so that by the depression of this plate by compressed air a, 95 uniform supply of adhesive is produced.

The valve is also connected with the disengaging rod 21 of the cigarette machine by the rod 20, so that on the stoppage of the machine by which the disengaging rod is ac- 100

tuated the valve is also moved into the closed position by which the compressed air is cut off from the magazine 7.

Instead of the double valve 13, 13' a single valve can be employed; in that case, however, it must be ensured that the two link systems 14—18 and 20, 21 operate on the valve independently of one another.

Finally, mention should be made of the reducing valve 22 which in known manner allows of the exact regulation of the compression.

Having thus described the nature of the said invention and the best means I know of carrying the same into practical effect, I claim:

1. An adhesive applying device for cigarette machines in which the adhesive is forced out of a reservoir into a distributing nozzle, characterized in that the reservoir located over the supply of adhesive communicates with a compressed air pipe which in order to remove the air pressure from the adhesive is adapted to be closed by a controlled valve from the supply of compressed air and at the same time is connected with the outer air.

2. An adhesive applying device according to claim 1, characterized in that the movements of the control valve are controlled by the actuating mechanism in such manner that, when the machine is stopped, the valve is shut so that the supply of compressed air is cut off, and also there is provided a hand-controlled device for the valves, the disengaging lever of which is actuated in the vicinity of the point where adhesive is applied so that the valve can be easily operated in conjunction with observation of the point where the adhesive is applied.

40 In testimony whereof I have signed my name to this specification.

CARL WILHELM MÜLLER.
